UNITED STATES PATENT OFFICE.

ERNEST G. H. SCHENCK, OF ORANGE, NEW JERSEY.

DIAMOND.

No. 809,531.

Specification of Letters Patent.

Patented Jan. 9, 1906.

Application filed May 3, 1904. Serial No. 206,200.

To all whom it may concern:

Be it known that I, ERNEST G. H. SCHENCK, a subject of the King of Belgium, residing at Orange, New Jersey, have invented certain 5 new and useful Improvements in Diamonds, of which the following is a clear, full, and exact description.

My invention relates to an improvement in the cutting of diamonds; and my object is 10 to improve the cutting of the same, which will lessen the liability of chipping and which will increase the ease of polishing or repolishing the stone. My cutting may also add to the brilliancy of the stone.

15 My invention will be defined in the claims.

In the drawings, which show one embodiment of my invention, Figure 1 shows a side elevation of diamond having my improved cutting thereon and on top and bottom provided with the well-known "brilliant" cutting, all of the facets of which are flat. Fig. 2 is a top plan view.

In cutting diamonds it is important in order to attain great brilliancy that all parts 25 of the stone should be polished, as any part left unpolished detracts from the brilliancy. It has sometimes been the practice to make the bases of the facets lying adjacent to the girdle meet in a line or edge at the girdle, and 30 consequently such stone in plain view has been bounded not by a complete circle, but by a series of short straight lines. This is objectionable for one reason, because it results in the adjacent facets on top and bottom of the stone meeting in a sharp edge, which is extremely liable to, and usually does, chip during the ordinary wear of the stone, thus detracting somewhat from its brilliancy. With such a construction also the girdle of 35 the stone is bounded by a series of straight lines or edges, which is not so desirable a construction in point of brilliancy as a circular girdle. A stone having a circular polished girdle is a particular advantage because all 40 points of the girdle are therefore symmetrical with relation to the axis of the stone, and as its girdle is polished the brilliancy of the stone is increased over what it would be if such girdle were left unpolished and also 45 over what it would be if the girdle were not circular. Furthermore, if any rough or unpolished portions should be left at the girdle they would somewhat detract from the brilliancy of the stone.

50 By my invention I can avoid to a great extent the liability of chipping by forming on

the stone a curved and polished facet, which meets adjacent facets in obtuse angles, and if the facet is flat and lies in a curved plane the ease of polishing or repolishing the facet 60 is greatly increased. This is particularly so where the facet lies in a circular plane, such as the exterior of a cylinder or a frustum of a cone. A stone having a polished circular-girdle facet is particularly advantageous in 65 the setting of the stone, as the setter's tool, if such a circular-girdle facet were left unpolished, would be extremely liable to catch on the stone and chip the same. This is a great disadvantage in setting a stone with an un- 70 polished girdle-facet; but in the form of my stone, which has a circular polished girdle facet, this liability of chipping is avoided, as the setter's tool cannot catch on the facet, as the same is polished, and therefore smooth. 75 This is a distinct advantage which will be appreciated by diamond-setters.

Referring to the drawings, 1 is a curved and polished facet, which in the embodiment shown runs entirely around the stone 80 at its girdle and lies in a curved plane—in this instance a circular plane—whose axis is substantially coincident with the axis xx of the stone. The stone at at least one side of the facet 1 may be provided with a plurality of 85 flat facets, which cut this girdle-facet in curved edges, as shown, and preferably both sides—that is, both top and bottom—are cut with such flat facets, and I preferably cut a continuous series of these flat facets entirely 90 around the stone, as shown at 2 6 7 8, &c. This curved facet 1 is preferably so cut that it forms obtuse angles, as illustrated by the lines 4 5, with the adjacent facets in order to avoid sharp edges and consequent liability 95 of chipping. In the embodiment illustrated each of the facets on top and bottom of the stone is flat, and the facet 1 meets every adjacent facet in an obtuse angle, as shown.

A diamond provided with a flat facet extending entirely around the stone and lying in a circular plane is of particular advantage in the polishing of the stone. It very often happens that small spots or other flaws occur in a diamond close to the girdle, and in 105 diamonds as cut before my invention the polisher might not be able to discover these flaws until his stone was entirely polished, when it would be too late to remove these defects without changing the proportion of the 110 stone and losing much of the material thereof. By my construction, however, such im-

perfections are readily discovered, and even in a diamond completely cut and polished such a circular facet running entirely around the stone makes it very easy to determine as

5 to whether or not the diamond is entirely without flaws at this point. This is an important advantage, as in a diamond the polishing must take place across the grain of the stone, and this grain runs in different directions at different points in the stone. I desire to limit myself to a diamond in distinction to any other stone, as a diamond has qualities inherent in it which are peculiar to it alone.

15 It will be obvious that the cutting of the facets on top and bottom of the stone need not be of the form or arrangement shown in the drawings, as it will be obvious that other cuttings on top and bottom may be provided 20 without departing from the scope of my invention as claimed.

What I claim is—

1. A diamond having a curved and polished facet running at least part way about 25 the girdle, and provided on its top and bottom with flat polished facets which meet said girdle-facet in curved edges.

2. A diamond having a curved and polished facet running entirely around the same 30 at its girdle and provided at at least one side thereof with flat, polished facets which meet said girdle-facet in curved edges and at obtuse angles.

3. A diamond having a flat polished facet 35 lying in a curved plane and running at least

part way around said stone, and provided at at least one side thereof with flat polished facets which meet said facet in curved edges and at obtuse angles.

4. A diamond having a flat, polished facet 40 lying in a circular plane substantially concentric with the axis of the said stone and running entirely around its girdle, and provided on its top and bottom with flat, polished facets which meet said girdle-facet in 45 curved edges and at obtuse angles.

5. A diamond having a flat, polished facet lying in a circular plane running entirely around the same, said stone at at least one side of said facet being provided with a plurality of flat and polished facets each of which 50 meets said circular facet in a curved edge and at an obtuse angle.

6. A diamond having a flat, polished facet lying in a circular plane running entirely 55 around the same at its girdle and whose axis is substantially coincident with the axis of said stone, said stone being provided on both top and bottom thereof with a continuous series of flat and polished facets entirely 60 surrounding said girdle-facet, each of which facets meets said girdle-facet in a curved edge and at an obtuse angle.

Signed at New York, N. Y., this 2d day of May, 1904.

ERNEST G. H. SCHENCK.
